ABSTRACT: A folder having opposed side sections which are maintained spaced apart by a strip of crushable material. The arrangement allows the placement of papers having a certain thickness inside of the folder followed by crushing of said strip to adjust the final thickness of the folder to that of the papers being stored therein.

PAPER STORAGE FOLDER

BACKGROUND OF THE INVENTION

Storage space for papers is becoming so increasingly expensive as time goes on that even a small saving of space in filing cabinets and the like is economically important. Various forms of filing folders and envelopes are known which receive papers for storage. Some of these are inconvenient to use and relatively costly. Some simpler folders have no provision for expanding or adjusting to take care of varying thickness storage materials. At least one known type of folder or envelope has pleated end walls to permit expansion but this construction has the disadvantage of awkwardness and the storage papers tend to be pinched or bound in the pleat folds.

The main objective of this invention is to provide a simplified and improved economical folder for papers which is adjustable readily as to thickness and which has the ability to receive papers and release them without pinching or binding. The invention structure is very economical to manufacture out of readily available materials and features a crushable spacer or separator element between two sides of the folder which allow the ultimate thickness to be regulated so as to meet particular needs without loss or waste of storage space.

Other features and advantages of the invention will be apparent during the course of the following description.

BRIEF DESCRIPTION OF DRAWING FIGURES

FIG. 1 is a perspective view of a paper storage folder according to one embodiment of the invention.

FIG. 2 is an enlarged fragmentary vertical section taken on line 2-2 of FIG. 1.

FIG. 3 is a section similar to FIG. 2 illustrating the crushing of the folder to reduce its thickness.

FIG. 4 is a perspective view of a folder in accordance with a second embodiment.

FIG. 5 is a sectional view similar to FIG. 2 taken on line 5-5 of FIG. 4.

FIG. 6 is a sectional view similar to FIG. 3 showing the crushing or compressing of the folder in FIG. 4 to adjust its thickness.

FIG. 7 is a perspective view of a further modified folder embodying the invention.

FIG. 8 is a fragmentary horizontal section taken on line 8-8 of FIG. 7.

FIG. 9 is a composite fragmentary perspective view of crushable spacer elements.

DETAILED DESCRIPTION OF THE PREFERRED EMBODIMENTS

Referring first to FIGS. 1 to 3 of the drawings wherein like numerals designate like parts, a paper storage folder 15 comprises opposed sections or sides 16, rectangular in form, and consisting of separate sheets of relatively stiff manila paper or the like. Disposed between the folder sides 16 along the bottom edges thereof is a filler or spacer element 17 of predetermined thickness and height adhesively secured to the interior faces of the folder sides 16, as indicated at 18. The element 17 which constitutes an essential feature of the invention is formed of relatively rigid material which will maintain its shape under normal conditions of use but has the ability to be crushed under a relatively mild compressive force to a reduced thickness and then to maintain such reduced thickness without substantial rebound or expansion, as exhibited in FIG. 3. The element 17 is formed ideally as a continuous strip or bar of foamed plastic cut to proper length for the folder and such materials as foamed polyurethane and foamed polystyrene and certain other plastics are suitable. Corrugated fiberboard and some forms of balsa wood also possess the inherent crushability or compressability required for the strip 17. In some cases, the element 17 need not be continuous and may be formed in short sections placed end-to-end.

In use, papers of known thickness are placed between the sides 16 and assuming that these papers do not fill the compartment between the sides 16, the folder may be crushed with the foot or other convenient means to reduce its overall thickness as shown in FIG. 3, such thickness then conforming to the thickness of the papers being stored in the folder. When the pressure is removed from the crushable element 17, there will be very little, if any, expansion of the same due to the inherent nature of the material which is lightweight and relatively rigid. When this material is crushed, its internal cells break down permanently and the material does not expand appreciably when the compressive force is removed.

The elements 17 may be provided in varying thicknesses ranging from a small fraction of an inch to three-fourths of an inch or more. Additionally, the height of the filler element may be varied to accommodate different widths of papers which it may be desired to store in the folder and to have edge portions of the papers visible at the open top of the folder as 15 where the same is placed in a file cabinet with the strip 17 arranged downwardly. FIG. 9 of the drawings shows crushable filler strips or bars A, B and C of successively increased thickness and height to illustrate the above point. In this manner, a storage folder of increased utility and one which saves a lot of space otherwise wasted is provided in a very economical manner. Furthermore, the invention folder is handy to use and papers placed therein do not tend to stick within a crease, pleat or fold.

FIGS. 4 through 6 show a modification of the invention 30 where a manila paper folder 19 is formed of a single sheet 20 folded around a relatively thick crushable filler strip 21 and adhesively bonded thereto as shown in FIG. 5. FIG. 6 shows the crushed condition of the folder and filler strip after a compressive force is applied thereto. As shown in FIG. 5, the folder has a rounded bottom 22 as distinguished from an abrupt crease or fold. In all other respects, the folder and its use is substantially identical to FIGS. 1 to 3 and no further description is thought to be necessary.

FIGS. 7 and 8 show a further feature wherein a folder 23 is formed of separate side portions 24 and 25 having a crushable filler strip or spacer 26 adhesively mounted along the lower edge portions of the sides as previously described. Additionally, crushable strips 27 of the same material above described are provided along one end or both ends of the folder and adhesively secured to one of the sides 24 or 25, as shown. This arrangement forms a top opening cavity or chamber 28 for papers and aids in guiding the papers into the folder and prevents their endwise displacement therein. 40 Preferably, the strips 27 and 26 have the same thickness and the same degree of crushability enabling the folder 23 to have its thickness adjusted as above described by compressing all of the strips 26 and 27 with the foot or the like. In some cases, both walls 24 and 25 may adhere to the end strips 27, in which case the device is no longer a folder but becomes an adjustable thickness envelope having a top opening.

It is now believed that the several features and advantages of the invention will be apparent to those skilled in the art without the need for further description.

I claim:

1. A storage receptacle for papers comprising a body portion having opposed side walls which are substantially coextensive in area and adapted to receive papers to be stored therebetween, and a crushable filler element disposed between said side walls along edge portions thereof and maintaining the side walls initially spaced apart a predetermined distance and being secured to at least one side wall, said filler element formed of a material which is readily compressible and has extremely little tendency to expand toward its original thickness after compression.

2. The structure of claim 1, wherein said storage receptacle is in the form of a folder having separate side wall sections, said sections adhesively bonded to the filler element along 75 corresponding edge portions of said sections.

3. The structure of claim 2, wherein said folder comprises a single sheet body portion formed around said filler element and being adhesively bonded to at least one side of the filler element and the filler element being crushable so that the thickness of the folder is adjustable.

4. The structure of claim 1, wherein the filler element is formed of cellular plastic material.

5. The structure of claim 1, and an additional filler element between said side walls along at least one end portion of the

receptacle, said additional element substantially at right angles to the first-named filler element and being crushable and being substantially of the same thickness as the first-named element.

5 6. The structure of claim 1, wherein said receptacle is an envelope of variable thickness open along one edge thereof and having variable thickness crushable filler strips along the other three edges thereof, said envelope being rectangular.
